UNITED STATES PATENT OFFICE.

ADOLPH A. GAZDA, OF PITTSBURGH, PENNSYLVANIA, ASSIGNOR TO WESTINGHOUSE ELECTRIC AND MANUFACTURING COMPANY, A CORPORATION OF PENNSYLVANIA.

ELEVATOR-CONTROL SYSTEM.

1,390,526.

Specification of Letters Patent. Patented Sept. 13, 1921.

Application filed January 5, 1918. Serial No. 210,530.

To all whom it may concern:

Be it known that I, ADOLPH A. GAZDA, a citizen of the United States, and a resident of Pittsburgh, in the county of Allegheny and State of Pennsylvania, have invented a new and useful Improvement in Elevator- 5 Control Systems, of which the following is a specification.

My invention relates to control systems and particularly to control systems for accelerating electric motors and for bringing the same to rest by dynamic braking.

My invention is particularly applicable to elevators, hoists and similar machines.

In present commercial arrangements, the 15 brake coil is operated through relays controlled by a mechanism which controls also the contact members of the main switches. It is an object of my invention to dispense 20 with these relays and to so simplify the connections that the mere opening of the main contact members directly releases the brake.

Another object of my invention is to make use of the starting resistor in dynamic 25 braking, thereby limiting the braking current which flows through the dynamic-braking resistor.

During the acceleration or the deceleration of a motor, as successive increments of 30 the resistor are removed from, or inserted into, the armature circuit, the motor is subjected to sudden rushes of current. In the case of an elevator, for example, the effect is to cause the elevator to move by jerks and 35 jumps. One of the objects of my invention is to reduce this effect to a minimum.

Other objects of my invention will be apparent from the following description when taken in connection with the accompanying 40 drawings.

In the drawings, Figure 1 is a diagrammatic view of a schematic arrangement according to my invention; Fig. 2 is a diagrammatic view of the motor circuit in the 45 braking or "off" position, and Figs. 3 to 6 are diagrammatic views of the various circuits completed through the motor during acceleration and deceleration.

Line conductors 1 and 2, which may be 50 connected to any suitable source of current, supply power to an electric motor having an armature 3 and a shunt field winding 4. The motor may be operatively connected, for example, to an elevator car. The direction 55 of rotation of the motor is controlled by re-

versing switches 5, 6, 7 and 8, the switches 5, 7 and 9 being mechanically connected, as are also the switches 6, 8 and 10. The switches 9 and 10 connect the braking resistor 20, hereinafter referred to, in a dynamic-braking circuit when the reversing switches are open.

A sectional starting resistor 11, which is in series with the armature 3, is controlled by a series of electromagnetic switches 12, 13 and 14. An induction coil 16 is connected in the motor circuit between the armature 3 and the resistor 11, and following the shunting of the resistor 11, is shunted by switch 15. A resistor 17, which is in parallel with the motor armature and the induction coil, is controlled by a plurality of electromagnetic switches indicated at 18 and 19. By this arrangement, the reversing switches do not break any induction circuits. In the circuit of the field winding 4 may be inserted shunt or series resistors, or both, and the field winding may, if desired, be composed of two parts, a standing field and an extra field. A dynamic braking resistor, 80 as shown at 20, is connected in parallel circuit with the armature 3 and the resistor 11 between the switches 6 and 8 or 5 and 7, respectively. A brake coil 21 is connected, at one end, to one end of the resistor 20 and, at 85 the other end, to the line. The brake coil 21 may be provided with resistors in series and in shunt, which resistors, for the sake of simplicity, have been omitted from the drawing. The electromagnetic switches 12 to 15 may be actuated by a series of coils which are controlled by auxiliary switches, the coils of which may be inserted in the armature circuit between the induction coil and the resistor 11. The usual emergency 90 and limit switches have been omitted from the drawings, as they form no part of the present invention. One limit switch, for example, may be located at 22.

It will be noted that, by connecting the 100 brake coil 21, at one end, to the dynamic-braking resistance, and, at the other end, to the line, I am enabled to operate the coil 21 independently of the relays customarily employed, by the mere opening or closing 105 of switches 6 and 8, and 5 and 7, respectively. If desired, however, for safety's sake, one or more relay switches may also be employed, as at 23.

Assuming that the various switches are in 110

the "off" position, indicated by Fig. 1, a dynamic braking circuit is established, as shown in Fig. 2, through the armature 3, the induction coil 16, the resistor 11 and the 5 braking resistor 20. By thus connecting the resistor 11 between the reversing switches 5 and 7, the dynamic-braking circuit of Fig. 2 becomes reestablished.

55

I claim as my invention:

1. In a control system, a motor circuit including a source of power, a dynamic-brake resistor, and a brake coil permanently connected, at one end, to said resistor and, at 60 the other end, to said source of power.
  2. The combination with a source of energy, an electric motor having a starting resistor and a dynamic-braking resistor, and means for connecting said motor to 65 said source, of means for connecting the armature of said motor in circuit with both said resistors upon said connecting means becoming inoperative.
  3. In a motor-control system, the combination with a source of power, an armature winding, and an induction coil and a starting resistor in series therewith, of a dynamic-braking resistor in parallel relation with said armature, said induction coil and 75 said starting resistor, and a brake coil connected, at one end, to said dynamic braking resistor, and, at the other end, to said source of power.
  4. The combination with a source of 80 power and a motor having an armature, of a dynamic-braking resistor in parallel relation with said armature, and a brake coil connected, at one end, to said dynamic-braking resistor, and, at the other end, to 85 said source of power.
  5. An electric circuit including an armature, an induction coil in series therewith, and a resistor in parallel circuit with said armature and said coil.
  6. In a control system, a pair of switches, an armature and an induction coil between 90 said switches, and a resistor in parallel circuit with said armature and said coil.
- In testimony whereof, I have hereunto 95 subscribed my name this 21st day of Dec. 1917.

ADOLPH A. GAZDA.
